UNITED STATES PATENT OFFICE.

ERWIN P. HESS, OF SOUTH BETHLEHEM, PENNSYLVANIA, ASSIGNOR TO BETHLEHEM STEEL COMPANY, OF SOUTH BETHLEHEM, PENNSYLVANIA, A CORPORATION OF PENNSYLVANIA.

PUMP MECHANISM FOR HYDRAULIC JACKS AND LIKE APPARATUS.

1,080,062.

Specification of Letters Patent.

Patented Dec. 2, 1913.

Application filed February 17, 1912. Serial No. 678,325.

To all whom it may concern:

Be it known that I, ERWIN P. HESS, a citizen of the United States, residing at South Bethlehem, Northampton county, 5 State of Pennsylvania, have invented certain new and useful Improvements in Pump Mechanism for Hydraulic Jacks and like Apparatus, of which the following is a specification.

10 My invention relates to improvements in pumps and is designed to provide pump mechanism of a novel and efficient character for effecting the operation of hydraulic apparatus such as jacks, presses, elevators, 15 cranes, punches, riveters, etc., or for other purposes, as for example, to force fluid into a pressure tank.

20 A further object of my invention is to provide pump mechanism of this character by which the speed of the ram or plunger of the jack or other apparatus, may be automatically reduced in proportion to the load being lifted.

25 The power of a hydraulic jack, press or the like being inversely proportional to the speed of its ram travel, a small unit lift is necessary when the load is heavy and my invention provides a pump which is so arranged that the volume of liquid forced under the ram is automatically increased under a light load, but, is reduced with a heavy load to meet the varying conditions of usage.

30 The nature of my invention will be best understood by referring to the accompanying drawing, in which I have shown an embodiment thereof, it being understood, however, that various changes may be made in the details of construction and arrangement of the parts of the mechanism without deviating from the spirit and scope of my invention.

35 Figure 1 is a vertical sectional view showing one embodiment of the invention, in which the improved pump is shown as applied to a hydraulic jack. Fig. 2 is a detail sectional view of the pumping mechanism and its connection to the jack cylinder or casing.

40 In the drawing the numeral 10 designates 50 a hollow jack cylinder or casing adapted to contain fluid under pressure which is provided with an integrally closed bottom or base 11 and is open at the opposite end.

Operating within the cylinder 10 is an outer cylindrical ram or sleeve 12 having a lower 55 enlarged portion or flange 13 which engages a stop collar 14 which is screwed within the upper end of the cylinder 10 and projects into the cylinder to act as a stop against the flange 13. The outer ram or sleeve 12 60 is provided with a plurality of projections 12' at its lower end, whereby the ram rests on the inner bottom surface of the cylinder 10 and permits fluid pressure to be applied to the lower end of the sleeve 12. Adjacent 65 its lower end the outer ram is also provided with a cup packing 15 held in place by a washer 16 and nut 17, which latter screws on the ram 12.

70 Fitted within the sleeve 12 is a hollow cylindrical inner ram or piston 18 which has an integral bottom 19 and at its upper end is provided with an enlarged and outwardly extending head 20 which is screwed onto the upper end of the inner ram 18. 75 The head is provided with the filling plug 21. At its lower end the inner ram is provided with the cup packing 22 and to secure the same into position I provide the washer 23 and nut 24 similar to that on the sleeve 80 12. The interior of the hollow inner ram 18 constitutes a cistern 25 for fluid supply and as will be hereinafter described the cistern communicates with a lifting chamber 26 below the two rams. 85

85 Formed integral with the bottom of the ram 18 and projecting inwardly and centrally thereof is a high pressure pump cylinder and low pressure piston 27 which forms the high pressure chamber 90 28. The inlet valve for the high pressure pump chamber 28 is indicated at 29 and the discharge or outlet valve for said chamber is shown at 30. These valves are spring pressed and seat upwardly 95 in their respective chambers 31 and 32 which are bored in the hollow inner ram 18. The lower ends of the chambers 31 and 32 are closed by the screw plugs 33 and 34, the latter being provided with grooves or channels 35, whereby the chamber 32 is at all times in communication with the lifting chamber 26. The valve chamber 31 has a passage port 36 which leads into the chamber 28 of the combined cylinder and low pressure piston 27, whereby the chamber 28 100 105

may communicate with the cistern 25 when the valve 29 is unseated. Located centrally within the hollow inner ram is the high pressure pump rod 37, the lower end thereof constituting the high pressure piston 38 which reciprocates in the high pressure cylinder 27. Secured to the high pressure piston rod 37 is a combined cylinder and valve sleeve 39 which has its vertical axis parallel and aligned with the axis of the high pressure piston 38 and of the combined cylinder and low pressure piston 27. The lower portion of the combined cylinder and valve sleeve 39 has a cup packing 40 and a nut 41 at its lower end to prevent leakage and may work against a bushing 42 on the outer surface of the cylinder 27. The low pressure cylinder 39 provides a low pressure pump chamber 43 within the same and has an inlet valve 44 seating upwardly in the plug 45 in said low pressure cylinder and controls a port 46 communicating with the low pressure pump chamber 43. The pump chamber 43 is provided with an escape port or passage 47 leading into the cistern 25 of the hollow ram. The passage 47 is normally closed by a spring-seated valve 48 guided in a plug 49 and seating downwardly and held to its seat by the lower spring cap 50 and spring 51 and the adjustable upper spring cap 52. This arrangement allows adjustment of the tension of the spring 51 and lower valve cap 50, whereby the desired pressure on the release valve 48 is procured so as to hold the same seated until the pressure exerted in the low pressure cylinder 39 is of such magnitude as to overcome the tension of the spring 51 forcing the release valve 48 from its seat and allowing the fluid to escape into the cistern 25. The high pressure piston 38 is provided with a vertical port or passage 53 which communicates at its upper end with the low pressure pump chamber 43 by means of one or more ports or passages 54 and which at its lower end opens into the high pressure pump chamber 28 through the discharge valve 55 which is provided with an enlarged head 55'. The discharge valve 55 seats upwardly in the passageway 53 and a hollow screw plug 56 prevents the valve from dropping out. The screw plug 56 holds the packing material 57 in place and also provides a passageway 58 by means of which the passage 53 communicates with the high pressure chamber 28. The pump rod 37 is provided at its upper end with a horizontally extending eye 59 which is engaged by a rocker arm 60 projecting from a rocker shaft 61. The rocker shaft is provided with the usual operating handle 62 at its outer end and has a projection 63 engaging a stop 64 on the head 20 to limit the downward movement of the handle. The stem of the valve 29 extends up-

wardly into the chamber or cistern 25 directly below the lower end of the cylinder 39 and the stem of the valve 30 projects upwardly into the chamber 28 directly below the piston 38. The said valve stems are normally not engaged by the cylinder 39 or piston 38, on account of the stop 64. However, on reversing the position of the handle the cylinder 39 and piston 38 may be lowered sufficiently far to engage the stems of the valves 29 and 30 and hold the passageways they control open. The load on the ram will then force liquid in the lifting chamber 26 past the valve 30, and thence outwardly from the high pressure pump chamber 28 through the port or passage 36 past the valve 29 into the lower portion of the cistern or reservoir 25. In the arrangement the low pressure pump chamber 43 has a larger volume than the high pressure pump chamber 28 which provides for a comparatively rapid lifting of the ram so that a light load can be raised rapidly or the ram run out rapidly to the load. The high pressure pump cylinder 27 constitutes the low pressure pump piston and it will therefore be seen that the pump is a telescopic duplex pump, fluid being forced underneath the inner and outer rams from the pump chambers 43 and 28 on the down stroke. In order to force fluid from the cistern or reservoir 25, which has been previously filled with a suitable operating fluid, under the hollow rams 12 and 18 the device operates as follows: Upon the upward stroke of the pump rod 37 and cylinder 39 the valves 29 and 44 will be unseated and the fluid from the chamber 25 will flow into the low and high pressure pump chambers 43 and 28. On the down stroke of the piston 38 and cylinder 39 the valves 29 and 44 are closed and the discharge valve 30 and valve 55 controlling the passageway 53 will be forced from their seats by the flow of liquid from the low pressure pump chamber 43 through ports 54 and passageway 53. The fluid will then enter the lifting chamber 26 through the ports 54 and 53, past the valve 55 and valve 30 and ports 32 and 35. Since the low pressure chamber 43 is of greater volume than the high pressure chamber 28 a comparatively rapid lifting of the rams is provided for, whereby a light load can be raised rapidly or the ram run out rapidly to the load. When, however, the load on the ram increases beyond the point at which the valve 48 is set to open, said valve will open and a large part of the liquid in the pump chamber 43 instead of passing downwardly into the lifting chamber 26 will pass out into the cistern or reservoir 25 through the port 47. Therefore, the fluid from the high pressure chamber 28 only is used to raise the rams. It will be noted also that when the pressure in the high pressure chamber 28 is of such 130

magnitude as to nearly neutralize the pressure in the low pressure chamber 43, the valve 55 will be held to its seat by the excess pressure on the head 55' of the valve due to the difference in areas of the upper and lower portions of the valve. In order to lower the ram the operating lever 62 is reversed to allow a longer down stroke of the cylinder 39 and the high pressure piston 38 and they engage respectively with the upwardly projecting stems of the valve 29 and 30, unseating the latter and holding the same open. The pressure or load on the ram will force the liquid in the lifting chamber past the valve 30 through the passageway 36 and port 31 and return the same to the cistern or reservoir 25.

It will be seen that by the construction as shown, I am enabled to use both of the pumps to procure a quick movement of the ram without requiring any great power to bring the head or ram up to the work. It is possible by this arrangement to raise light loads rapidly and the speed will be automatically reduced in proportion as the load or thrust on the ram is increased and the excess fluid is returned from the low pressure cylinder to the reservoir.

Having thus described the invention what is claimed as new is:

1. In a device of the class described, in combination, a piston, a cylinder for said piston having an outlet, a second cylinder having an inlet movable with said piston, said cylinders telescoping one into the other, and means for establishing communication between the cylinders.

2. In a device of the class described, in combination, a cylinder having an outlet, a piston reciprocable in said cylinder, a second cylinder having an inlet movable with said piston, said cylinders telescoping one into the other, means for controlling the pressure in one of said cylinders, and means for establishing communication between said cylinders.

3. In a pumping mechanism, the combination of a cylinder having an inlet and outlet, a plunger reciprocable in said cylinder, a cylinder having an inlet and outlet carried by said plunger, said cylinders telescoping one into the other, one of said cylinders constituting the plunger for the other cylinder, and means for establishing communication between the cylinders.

4. In a pumping mechanism, the combination of, a high pressure cylinder having an inlet and outlet, said high pressure cylinder constituting a low pressure piston, a piston reciprocable in said high pressure cylinder, a low pressure cylinder carried by said high pressure piston and having an inlet and outlet, and means for establishing communication between said low pressure and high pressure cylinders.

5. In a pumping mechanism, the combination of, a cylinder having an inlet and outlet, a plunger reciprocable in said cylinder, a second cylinder having an inlet and outlet movable with said plunger, said cylinders telescoping one into the other, said first-named cylinder constituting the plunger for the second cylinder, means for relieving the pressure in one of said cylinders, and means for establishing communication between said cylinders.

6. In a pumping mechanism for hydraulic apparatus, in combination, a cylinder having an inlet and outlet, a plunger reciprocable in said cylinder, a second cylinder having an inlet and outlet movable with the plunger, said cylinders telescoping one in the other, and means in the plunger for establishing communication between the cylinders.

7. In a pumping mechanism for hydraulic apparatus, in combination, a cylinder having an inlet and outlet, a plunger reciprocable in said cylinder, a second cylinder having an inlet and outlet movable with the plunger, a passageway for establishing communication between said cylinders, and means for regulating the amount of fluid flowing through said passageway.

8. In a pumping mechanism for hydraulic apparatus, in combination, a cylinder having an inlet and outlet, a plunger reciprocable in said cylinder, a second cylinder having an inlet and outlet movable with the plunger, a passageway for establishing communication between said cylinders, and automatic means for regulating the amount of liquid flowing through said passageway.

9. In a pumping mechanism for hydraulic apparatus, in combination, a cylinder having an inlet and outlet, a plunger reciprocable in said cylinder, a second cylinder having an inlet and outlet, said cylinders being relatively movable, said plunger having a passageway therein for establishing communication between said cylinders, and pressure-controlled means for regulating the amount of fluid flowing through said passageway.

10. In a pumping mechanism for hydraulic apparatus, in combination, a cylinder having an inlet and outlet, a piston reciprocable in said cylinder, a second cylinder having an inlet and outlet and having a greater working fluid capacity than said first-mentioned cylinder, said cylinders being relatively movable, means for establishing communication between said cylinders for the transfer of fluid, and means for regulating the amount of fluid transferred.

11. In a pumping mechanism for hydraulic apparatus, in combination, a cylinder having an inlet and outlet, a piston reciprocable in said cylinder, a second cylinder having an inlet and outlet movable with said piston and having a greater working

- fluid capacity than said first-mentioned cylinder, said cylinders telescoping one in the other, means for establishing communication between said cylinders for the transfer 5 of fluid, and pressure-controlled means for regulating the amount of fluid transferred.
12. In a pump adapted to be submerged in a fluid, in combination, a cylinder having an inlet and outlet adjacent one end, a piston reciprocable in said cylinder and provided with a valved passageway, a second cylinder having an inlet and communicating with said first-mentioned cylinder through said passageway, said cylinders telescoping one in the other, and spring-pressed means for controlling the pressure in one of said cylinders.
13. In a pump adapted to be submerged in a fluid, in combination, a cylinder having 10 an inlet and outlet, a piston reciprocable in said cylinder, a second cylinder having an inlet, means for establishing communication between said cylinders, said cylinders telescoping one in the other, and adjustable 15 means for controlling the pressure in one of said cylinders.
14. In a pump adapted to be submerged in a fluid, in combination, a cylinder having an inlet and outlet, a piston reciprocable in 20 said cylinder, a second cylinder having an inlet, means for establishing communication between said cylinders through the piston, said cylinders telescoping one into the other, and adjustable spring-pressed means for 25 controlling the pressure in one of the cylinders.
15. In a pump for hydraulic apparatus, the combination of a cylinder having a valve controlled inlet, a piston movable in 30 said cylinder, a second cylinder having a valve-controlled inlet, means for establishing communication between said cylinders, and means on the second cylinder for unseating the valve of said first-mentioned inlet to permit the discharge of fluid from the 35 first-mentioned cylinder.
16. In a pump for hydraulic apparatus, the combination of a cylinder having a valve-controlled inlet, a piston movable in 40 said cylinder, a second cylinder movable with said piston and having a valve controlled inlet and a valve controlled outlet adapted to be opened at a predetermined pressure within the cylinder, said cylinders 45 having communication one with the other through said piston, and means for unseating the valve of said first-mentioned inlet to permit the discharge of fluid from the first mentioned cylinder.
17. In a pump for hydraulic apparatus, the combination of a cylinder having a valve-controlled inlet, a piston reciprocable in 50 said cylinder, a second cylinder connected to said piston and having a valve-controlled 55 inlet and an adjustable relief valve, said cyl-

inders having communication one with the other and telescoping one into the other, and means for unseating the valve of said first-mentioned inlet to permit the discharge of fluid from said first-mentioned cylinder. 70

18. In a device of the class described, the combination with a casing adapted to receive fluid under pressure, of a cylinder having communication with said casing, said cylinder having a valve-controlled inlet 75 connected with a source of fluid supply, a piston reciprocable in said cylinder, a second cylinder connected to said piston and having a valve-controlled inlet, said cylinders having communication one with the other and telescoping one into the other, and means for unseating the valve of said first-mentioned inlet to permit the return of the fluid in said casing to the source of supply. 80

19. In a device of the class described, the combination of a casing adapted to receive fluid under pressure, of a cylinder having a valve-controlled connection with said casing, a cistern adapted to contain a supply of fluid, said cylinder having a valve-controlled inlet connected with the cistern, a piston reciprocable in said cylinder, a second cylinder movable with said piston and having a valve-controlled inlet, said cylinders having communication one with the other, and means for unseating the valves of the valve-controlled connection and first-mentioned valve-controlled inlet to allow the return of the fluid in said casing to said cistern. 85

20. In a device of the class described, the combination of a casing adapted to receive fluid under pressure, of a cylinder having a valve-controlled connection with said casing, a cistern adapted to contain a supply of fluid, said cylinder having a valve-controlled inlet connected with the cistern, a piston reciprocable in said cylinder, a second cylinder connected to said piston and having a valve-controlled inlet, said cylinders having communication one with the other through said 100 piston and telescoping one into the other, and means for unseating the valves of the valve-controlled connection and first-mentioned valve-controlled inlet to allow the return of the fluid in said casing to said cistern. 105

21. In a device of the class described, the combination with a casing adapted to receive fluid under pressure, of a cistern adapted to contain a fluid supply, a cylinder 110 communicating with said casing, a piston reciprocable in said cylinder, a second cylinder having an inlet connected to said fluid supply, said second cylinder communicating with said first-mentioned cylinder to permit 115 the transfer of fluid to said casing from the cistern, the cylinders being relatively movable, means for regulating the amount of fluid transferred, and means for returning the fluid in the casing to the cistern. 120

22. In a device of the class described, the combination with a casing having an opening at one end and adapted to receive fluid under pressure, of a plunger fitted in said open end to close the casing and being movable in said casing, a cylinder in communication with said casing, a piston reciprocable in said cylinder, a second cylinder having an inlet movable with said piston, means for establishing communication between said cylinders to permit the transfer of fluid to said casing from said second cylinder, and means for regulating the amount of fluid transferred.
23. In a device of the class described, the combination with a casing having an opening at one end and adapted to receive fluid under pressure, of a plunger fitted in said open end to close the casing and being movable in said casing, a cylinder in communication with said casing, a piston reciprocable in said cylinder, a second cylinder having a fluid inlet carried by said piston, said cylinders telescoping one in the other, means for establishing communication between said cylinders to permit the transfer of fluid to said casing from said second cylinder, and pressure-controlled means for regulating the amount of fluid transferred.
24. In a device of the class described, the combination with a casing having an opening at one end and adapted to receive fluid under pressure, of a plunger fitted in said open end to close the casing and being movable in said casing, a cylinder in communication with said casing, a piston reciprocable in said cylinder, a second cylinder having a fluid inlet carried by said piston, said cylinders telescoping one into the other, means for establishing communication between said cylinders through said piston to permit the transfer of fluid to said casing from said second cylinder, and means controlled by the pressure of the fluid in said casing for regulating the amount of fluid transferred.
25. In a device of the class described, the combination with a casing having an opening at one end and adapted to receive fluid under pressure, of a plunger fitted in said open end to close the casing and being movable in said casing, a cylinder carried by said plunger and in communication with said casing, a piston reciprocable in said cylinder, a second cylinder having a fluid inlet movable with said piston and plunger, means for establishing communication between said cylinders to permit the transfer of fluid to said casing from said second cylinder through said first-mentioned cylinder, and means for varying the amount of fluid transferred.
26. In a device of the class described, the combination with a casing having an opening at one end and adapted to receive fluid under pressure, of a plunger fitted in said open end to close the casing and being movable in said casing, a cistern adapted to contain a fluid supply, a cylinder having connection with said cistern and being in communication with said casing, a piston reciprocable in said cylinder, a second cylinder having an inlet connected to said fluid supply, said second cylinder communicating with said first-mentioned cylinder to permit the transfer of fluid to said casing from both of the cylinders and cistern, said cylinders being relatively movable, means for varying the amount of fluid transferred, and means for returning the fluid in the casing to the cistern through said connection in the first-mentioned cylinder.
27. In a device of the class described, the combination with a casing adapted to receive fluid under pressure, of a cistern adapted to contain a fluid supply, a cylinder communicating with said casing, a piston reciprocable in said cylinder, a second cylinder movable with the piston and having an inlet connected to said fluid supply, said cylinders telescoping one in the other, said cylinders communicating one with the other to permit the transfer of fluid to said casing from the cistern, means for regulating the amount of fluid transferred, and means for returning the fluid in the casing to the cistern at will.
28. In a hydraulic apparatus, the combination of a motor cylinder, a ram working therein and having a cavity adapted to contain the motive fluid supply, a passageway connecting the cylinder and the cavity in the ram, and means for forcing the fluid from the cavity in the ram through the passageway to the motor cylinder to raise the ram, said means comprising a hollow plunger having a relief outlet therein and a relief valve controlling said outlet.
29. In a device of the class described, the combination of a cylinder adapted to receive fluid under pressure, a ram working in the cylinder, means for forcing fluid into the cylinder to move the ram comprising a hollow plunger having a fluid inlet and a relief outlet, and valves controlling said inlet and outlet.
30. In a device of the class described, the combination with a cylindrical casing open at one end, of a hollow ram working therein, a pump cylinder integral with the bottom of said ram and rising therefrom, said cylinder communicating with the casing, a piston operable in the cylinder, a second cylinder connected to said piston and having a fluid inlet, said cylinders having communication one with the other, and means for regulating the amount of fluid forced into the casing.
31. In a device of the class described, the

- combination with a cylindrical casing open at one end, of a hollow ram working therein, a pump cylinder integral with the bottom of said ram and rising therefrom, said cylinder communicating with the casing, a piston reciprocable in the cylinder, a second cylinder connected to said piston and having a fluid inlet, said cylinders having communication one with the other and telescoping one in the other and means, dependent on the thrust of the ram for regulating the amount of fluid forced into the casing.
32. In a device of the class described, the combination with a motor cylinder, of a hollow ram working therein, a pump cylinder integral with the bottom of said ram and rising therefrom, said pump cylinder communicating with said motor cylinder and with the interior of the hollow ram through valved passageways, a piston reciprocable in the pump cylinder, a second pump cylinder connected to said piston and having a fluid inlet and outlet, said pump cylinders having communication one with the other and telescoping one in the other whereby one of said pump cylinders constitutes the piston for the other, and means for regulating the amount of fluid discharged through said outlet.
33. In a hydraulic apparatus, the combination of a motor cylinder, a ram working in the motor cylinder and having a cavity adapted to contain the motive fluid, passageways connecting the cavity in the ram with the interior of the motor cylinder, a second cylinder disposed within the cavity and adapted to be connected with the interior of the motor cylinder through one of said passageways, means for forcing the motive fluid from the cavity in the ram through the second cylinder into the motor cylinder to raise the ram, said means comprising a plunger fitting the second cylinder, and means attached to the plunger for regulating the supply of motive fluid to the motor cylinder.
34. In a hydraulic apparatus, the combination with a motor cylinder, of a ram working therein, means including a pump rod, and a member for forcing fluid to the motor cylinder to move the ram, said member having openings therein, and means for regulating the amount of fluid delivered to the cylinder, said regulating means comprising a valve controlling one of said openings, a collar loosely mounted on said pump rod and bearing against said valve, another collar adjustably connected to the rod, and resilient means interposed between and tending to separate said collars and yieldably holding said valve to its seat.
35. In a hydraulic apparatus, the combination of a motor cylinder, a ram working in the motor cylinder and having a cavity adapted to contain the motive fluid, passageways connecting the cavity in the ram with the interior of the motor cylinder, a second cylinder disposed within the cavity and adapted to be connected with the interior of the motor cylinder through one of said passageways, means for forcing the motive fluid from the cavity in the ram through the second cylinder into the motor cylinder to move the ram, said means comprising a plunger having an annular cavity therein to receive the walls of said second cylinder and forming a chamber to receive motive fluid from said cavity in the ram, said chamber having a valved inlet and relief outlet and an outlet into the second cylinder, and means for operating said plunger.
- In testimony whereof I affix my signature in presence of two witnesses.
